Application April 11, 1950, Serial No. 155,238
In the Netherlands April 13, 1949

3 Claims. (Cl. 313—111)

1

This invention relates to electric incandescent lamps, particularly for use in vehicle lighting, which comprise at least one filament and a cup-shaped screen, and in which the filament is located between at least two lateral edges of the screen.

Such lamps are arranged in a spotlight or headlight in such manner that the filament extends substantially in the optical axis of the optical system of the spotlight. This optical system usually consists of a reflector shaped in the form of a paraboloid of revolution. The screen serves to prevent light from falling on one side of the reflector, thus obtaining the so-called "dipped" lighting, when the light is directed solely below the horizontal plane extending through the lamp. The screen generally consists of a metal cup-shaped hood, for example, of nickel, arranged in close proximity to the filament in the lamp. The screen is generally of a small size, in order to intercept a minimum quantity of light from a second filament generally provided in the lamp, called the "main filament" herein, which produces the "undipped" or normal beam. The first filament is called the "dipping filament" herein. If only the latter is provided in the lamp, there is generally no objection to making the screen considerably larger and applying it, for example in the form of a mirror or a layer of lacquer, on to the lamp bulb.

If a screen is arranged transversely of the optical axis of the lightbeam and at a distance, for example 10 m., in front of the lamp, a patch of light viz. the beam pattern is projected thereon. By operating alternatively one filament or the other, a so-called "main" and a "dipped" beam is produced respectively, the beam patterns of most lamps being substantially circular, semi-circular or approximately elliptical. It is to be noted that in the present case reference is made only to co-operation of the lamp with an optical system having rotational symmetry, such as the aforesaid reflector, in order to make the properties of the lamp better understood. Consequently no reference is made to the use of means, such as ribbed reflectors of front glasses, for directing the light.

The well-known lamps produce a "dipped" beam pattern having a comparatively large radius, i. e. that a greatly diffused beam is produced in a vertical downward direction, a large part of the light flux produced by the "dipping" filament being projected on to the road at a comparatively short distance in front of the vehicle. As a result of this illumination, the sensitiveness

of a driver's eyes adjusts itself to this bright illumination occupying a considerable part of his field of view, so that he is handicapped in observing more remote obstacles.

5 The invention has for its object inter alia to mitigate this limitation and to provide a construction of lamp which gives "dipped" lighting and permits the light to be radiated in the form of a beam, which is comparatively little diffused, and at a considerable distance in front of the vehicle.

According to the invention, the filament is located between at least two side walls of the screen, is V-shaped and extends in a plane which 15 is parallel to or coincides with the plane through the edges of the screen. In a normal head- or spot-light comprising a reflector in the form of a paraboloid of revolution, this lamp should be arranged such that the plane of the filament 20 extends horizontally slightly above the axis of the reflector and the top of the V-shaped filament is near the focus of the reflector, the limbs of the V extending on either side above the axis. This results in a beam pattern, the sectional 25 area of which is approximately semi-elliptical with a small elevation, the highest luminous intensity being just below the upper boundary. It is this luminous intensity which enables obstacles to be made visible at a great distance in front of the vehicle.

30 It is pointed out that V-shaped filaments are frequently used as main filament in lamps for vehicle lighting. This shape has also been used for the "dipping" filament but, for this purpose, not combined with a screen, and in a different position (British patent specification 440,956 and American patent specification 2,214,472). The filaments arranged between the edges of a screen were generally rectilinear (for example British patent specifications 442,939 and 393,886).

35 40 In order that the invention may be readily carried into effect, a number of examples will now be described more fully with reference to the accompanying drawings, in which:

45 Figs. 1 and 4 are diagrammatical vertical sections of headlights comprising a lamp of known type and of a variant thereof respectively;

Figs. 2 and 5 are plan views of these lamps;

Figs. 3 and 6 show the beam patterns produced

50 by these lamps;

Fig. 7 is a diagrammatical horizontal section of a lamp according to the invention without screen and "dipping" filament;

Figs. 8 and 10 show different forms of a "dipping" filament according to the invention;

55

Fig. 11 is a diagrammatical vertical section of a headlight comprising a lamp according to the invention;

Fig. 12 is a plan view of the lamp according to Fig. 11;

Fig. 13 shows the beam pattern of the lamp according to Fig. 11;

Fig. 14 is a diagram of the light distribution produced by a known lamp and by a lamp according to the invention;

Fig. 15 shows the beam pattern of an incandescent lamp comprising an asymmetrical V-shaped filament;

Fig. 16 is a plan view and

Fig. 17 a side view of an incandescent lamp and a screen of a lamp according to the invention;

Figs. 18 to 20 are a plan view and two side views respectively of the filament body and the screen of a lamp in a modified embodiment and

Fig. 21 is a plan view of a filament and screen in a third embodiment.

The lamp shown in Figs. 1 and 2 comprises a bulb 1, a main filament 2, a "dipping" filament 3, a screen 4, a cap 5 and a few parts (not shown) such as supporting wires for the filaments and the screen, and the pinch in which these wires are secured. The lamp is arranged in a reflector 6 having the shape of a paraboloid of revolution. The lamp is adjusted in a manner such that the main filament 2 is located at the focus F.

A light ray 7 from the main filament 2 will extend, subsequent to reflection by the reflector 6, parallel to the optical axis 8 of this reflector. A ray 9 from that part of the dipping filament 3 which is nearest to the focus F, extends, subsequent to reflection, in a slightly slanting downward direction, whilst a ray 10 from that end of the dipping filament body which is most remote from the focus F has a steeper slope.

In the present case, the filament 3 is located between the edges 11, 12 and 13 of the screen 4 (Fig. 2). These edges extend approximately in one plane with the filament. Only the edge 14 does not extend in the plane but extends in a higher plane, in order to prevent light directly from the filament 3 from shining on approaching traffic. These edges form the upper boundary of the side walls.

Where in the present specification reference is made to a filament extending in a plane, it should be considered that a filament naturally has certain dimensions and cannot coincide mathematically with a plane, so that such reference is to be taken colloquially.

The beam pattern produced by this known lamp consists of the images formed by various parts of the reflector of the filament. These images may be shown separately by shielding off the remaining reflector parts. Thus, vertically below the point of intersection 0 of the optical axis 8 with the screen, a series of images 15 is formed by the reflector parts located in or near the vertical plane through the optical axis 8. The series of images 16 and 17 through the said axis on either side of the lamp (i. e. under or above the plane of the drawing in Fig. 1). The reflector parts located between these limits form series of images, for example, the series 18 and 19. The whole light falls, however, below the horizontal plane through 0, owing to the presence of the screen 4 which prevents light from falling on the lower reflector part and owing to the position of the filament 3 in front of the focus F and slightly above the axis 8.

From the foregoing it will be seen that the diameter D of the "dipping" beam is substantially proportional to the length of the "dipping" filament L (Figs. 3 and 1). Due to the comparatively great length of such a filament, the beam has such a diameter that a great part of the light flux is projected on to the road at a short distance in front of the vehicle.

If the "dipping" filament is arranged transversely of the axis at the focus F, as shown in Figs. 4 and 5, this would yield the beam pattern shown in Fig. 6. The reflector parts located in or near the vertical plane through the axis 8 form elongated, horizontal images 20 of the filament 3; reflector parts located in or near the horizontal plane through the axis 8 produce comparatively short, compact images 21 near the axis passage 0. The intermediate reflector parts, consequently located in oblique planes through the axis, produce a number of oblique images 22 located in part above the horizontal plane through the axis. This proves that, in spite of the presence of the screen 4, a pure "dipped" lighting is not produced. Furthermore it is obvious that this effect is the more troublesome, according as the filament 3 (Fig. 5) is longer and protrudes more on either side of the axis.

On the other hand it appears from Fig. 1 that the reflected light from part of the filament is more reflected downward as this part is more located in front of the focus (see for example light rays 7, 9 and 10 in Fig. 1). The oblique images 22 (Fig. 6) can thus be prevented from extending above the horizontal plane by placing the filament body 3 at an adequate distance in front of the focus.

In this event, however, the images 20 also descend, so that an unduly strong front illumination is produced.

The invention is based on the recognition that the optimum beam pattern is produced, if the filament is kept within the limits of an angle 23 (Fig. 7), the apex of which is at the focus F and which extends on both sides of the axis 8. The ideal shape of the filament would consequently be a triangular luminous surface. Although such a filament is feasible, for example, in the form of a tungsten plate which is heated to a high temperature by the passage of current or by gas discharge, a sufficient approximation is obtained in practice with the use of a normal coiled filament which is bent with two limbs forming the said angle 23, as shown in Fig. 8. If the angle formed by one of the limits of the angle and the axis 8 be β (Fig. 7), it is found from experiments with different conventional reflectors that this angle may be between 60° and 15° (Figs. 9 and 10). In a very suitable form, $\alpha=30^\circ$ (Fig. 8). The V-shaped filament will usually be arranged symmetrically with respect to the axis of the lamp, but sometimes a non-symmetrical arrangement may be advantageous, for example to cause more light to shine on one road half than on the other road half.

Figs. 11 and 12 show diagrammatically the use of such a lamp in a reflector. The reference numerals correspond to those used in Figs. 1, 2, 4 and 5.

Fig. 13 shows the beam pattern produced by several parts of the reflector. The reflector parts located in or near the vertical plane through the axis produce a series of images 24. They are magnified images of the V-shaped filament. The reflector parts located in or near the horizontal plane through the axis are facing, as it

were, the side of the V-shaped filament and consequently do not reproduce a V but a rectangle so that two series of images 25 are produced to the left and to the right of the axis 0, of which only one series is shown. The intermediate reflector parts view, as it were, the filament body in an oblique direction so that the V is shortened with a smaller apex than the virtual one. Such reflector parts produce, for example, a series of images 26.

The better light distribution ensured by the use of a lamp according to the invention is illustrated in Fig. 14. The diagram shows the measuring results of the illumination intensity on a screen arranged at right angles to the axis of this beam light and at a distance of 10 m. in front thereof. The distances above and below the axis are indicated in cm. The beam light is arranged at the height of 1 m. The light striking the screen 20 cms. below 0 would strike the road at a distance of 50 m. in front of the vehicle, and the light striking the screen 80 cms. below 0 would strike the road at a distance of 12.5 m. in front of the vehicle.

The full line 27 indicates the illumination obtained with the use of a lamp hitherto employed, in which the straight "dipping" filament extends just above the optical axis (wire 3 shown in Figs. 1 and 2), whereas the broken line 28 indicates the illumination obtained with the use of a V-shaped "dipping" filament according to the invention (the wire 3 shown in Figs. 11 and 12). As appears from the points of intersection with the lines 29 and 30, which indicate the illumination intensity at distances of 50 and 12.5 m. respectively in front of the vehicle on the road, the former has become twice as high and the latter has decreased to one half.

The beam pattern shown in Fig. 10 and the diagram shown in Fig. 4 are obtained with the use of V-shaped filaments, the lengths of the limbs being equal. If the length of one of the limbs is increased relatively to that of the other, the diameter of the beam pattern again increases. This increase is generally undesirable, but in view of the fact that the radius of the beam pattern in one direction increases more than in the other, it may in some circumstances be an advantage to use an asymmetrical V, for example if it is desired to direct a stronger light flux to one side of the road. The beam pattern produced by such a lamp is shown in Fig. 15. The reflector parts located in or near the vertical plane through the axis produce a series of images 24' of the filament two of which are shown. The reflector parts extending in or near the horizontal plane through the axis produce two series of images 25' and 25'' which are asymmetrical, similarly to the filament. The reflector parts extending in oblique planes through the axis produced series of images 26' and 26''. From the figure it appears that the vertical diffusion is still smaller than that of a suitable filament (Fig. 3), and show that an improvement in luminous intensity is obtained close below the horizontal outline of the beam.

The methods of construction of a lamp according to the invention need not depart considerably from the methods used for known lamps comprising a "dipping" filament. In the latter, one end of the straight filament is usually welded to the screen, while the other end is secured to a terminal wire. The V-shaped filament in the lamp according to the invention may be suspended in the same manner, as shown in Fig. 15.

The screen 4 is secured at one side to a supply conductor 31 and the V-shaped filament 3 is suspended between one of the edges of the screen and a second supply conductor 32. The shape of the screen is matched to that of the filament, so that the edges 13 and 13' extend parallel to the limbs of the wire.

A further construction is shown in Figs. 18, 19 and 20. The ends of the filament 3 are each secured to a supply conductor 31 and 32 respectively. This permits more freedom in the arrangement of these ends than in the constructions shown in Figs. 16 and 17, in which one end invariably lies on edge of the screen. (At this end a stay wire could, of course, be welded to the screen, but then an additional element is required.) In the construction shown in Figs. 18 to 20 the screen 4 is provided at the rear side and the top with a groove or indent which is prolonged about the edge formed by the transition of these sides. The stay wire 31 is secured by welding in this groove. In this way the position of the screen is fixed unequivocally prior to the welding operation.

In the construction shown in Fig. 21, the filament body comprises two parallel filaments 3' and 3''. The top of the V is connected to the supply conductor 32, the free ends to the screen 4. The screen is again provided with a groove, in which the bent end of the supply conductor 31 is secured.

Such a construction has the advantage that the burning out of one of the limbs of the filament results only in a decrease in light output of the lamp but not in its extinction.

In order to relieve the filament as much as possible of mechanical loads due to vibration of the filament joints, particularly since the supply conductor supporting the screen will vibrate with a frequency and amplitude differing from those of the other supply conductor, it is advisable to provide an insulating, mechanical joint between the ends of these supply conductors, for example in the manner shown in Figs. 17 and 18, where a stay rod 33 is welded to one supply conductor 32 and a stay rod 34 is welded in the screen 4. The two rods are connected together by means of an insulating glass bead 35. This construction, which is known per se (for example British patent specification 393,886) may, of course, also be used in the lamps shown in Figs. 18 to 21.

What I claim is:

1. An incandescent lamp for use with a reflector having an optical axis comprising a bulb, a main filament near the focal point of said reflector, a cup-shaped screen within said bulb, a V-shaped filament located between two lateral edges of said screen, each of said main filament, said V-shaped filament and said optical axis lying in the same plane, said V-shaped filament having its apex pointing toward said main filament and the angle between one of the limbs of the V-shaped filament and the optical axis on the side of the V-shaped filament facing away from the reflector being between 15° and 60°.

2. An incandescent lamp for use with a reflector having an optical axis comprising a bulb, a cap for said bulb, the axis of said cap being coincident with the optical axis of said reflector, a main filament, a cup-shaped screen within said bulb, a V-shaped filament located between two lateral edges of said screen, each of said main filament, said V-shaped filament and said cap axis lying in the same plane, said V-shaped fila-

ment having its apex pointing toward said main filament and the angle between one of the limbs of the V-shaped filament and the axis of the cap on the side of the V-shaped filament facing away from the reflector being between 15° and 60°.

3. An incandescent lamp for use with a reflector having an optical axis comprising a bulb, a cap for said bulb, the axis of said cap being coincident with the optical axis of said reflector, a main filament located at the focal point of said reflector, a cup-shaped screen within said bulb on the side of said main filament remote from said reflector, a V-shaped filament located between two lateral edges of said screen, each of said main filament, said V-shaped filament, said lateral edges and said axis lying in the same plane, said V-shaped filament having its apex pointing toward said main filament and the angle between one of the limbs of the V-shaped filament and

the axis of the cap on the side of the V-shaped filament facing away from the reflector being between 15° and 60°.
